Patented Mar. 14, 1916.

*Inventor,
Harry C. Adam.
By Baskerville & Church Lithos.*

UNITED STATES PATENT OFFICE.

HARRY C. ADAM, OF ST. LOUIS, MISSOURI.

DESIGN FOR A LIGHTING-FIXTURE.

48,699.

Specification for Design.

Patented Mar. 14, 1916.

Application filed October 8, 1915. Serial No. 54,906. Term of patent 14 years.

To all whom it may concern:

Be it known that I, **HARRY C. ADAM**, a citizen of the United States, residing at St. Louis, Missouri, have invented a certain new, original, and ornamental Design for Lighting-Fixtures, of which the following is a specification, reference being had to the accompanying drawing, forming part thereof.

The figure of the drawing is an elevational view of my new design for a lighting fixture.

I claim:

The design for a lighting fixture, as shown.
HARRY C. ADAM.

Witnesses:

WELLS L. CHURCH,
GEORGE BAKEWELL.
